DESIGN FOR A CAPE.

Design No. **6,681**, dated May 27, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. **6,681**, dated May 27, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The figure in the accompanying drawing clearly represents my design for a circular garment or cloak, the main peculiarity of which is the character of the deep fringe A, with which the semicircular outline of the garment is bound, and which is also used in the ornamentation of the hood B. This fringe is composed of a narrow giup-like portion, a, which is sewed to the garment, and of long twisted ends b, which hang loosely from the said portion a.

The hood B is of the peculiar shape represented, and is ornamented by cords and tassels, as clearly shown in the drawing.

Irrespective of the colors employed, I claim—

The design for a garment, substantially as described, and represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
